UNITED STATES PATENT OFFICE.

LOUIS LEVY, OF NEW YORK, N. Y., ASSIGNOR TO SOLOMON SCHEUER, OF NEW YORK, N. Y.

DESIGN FOR A TOY.

41,190.

Specification for Design. Patented Feb. 21, 1911.

Application filed December 5, 1910. Serial No. 595,792. Term of patent 7 years.

To all whom it may concern:

Be it known that I, LOUIS LEVY, a citizen of the United States, residing at New York city, borough of Manhattan, in the county and State of New York, have invented a new, original, and ornamental Design for a Toy, of which the following is a specification, reference being had to the accompanying drawing, forming part thereof.

The figure is a perspective of a toy, showing my new design.

I claim:

The ornamental design for a toy, as shown.

LOUIS LEVY.
